CLAIM

The ornamental design for a combination high chair, rocking horse, and desk, as shown and described.

DESCRIPTION

FIG. 1 is a front right perspective view of the combination high chair, rocking horse, and desk of FIG. 1 showing our new design as a high chair;

FIG. 2 is a bottom right perspective view of the combination high chair, rocking horse, and desk of FIG. 1 showing our new design as a rocking horse;

FIG. 3 is a rear right perspective view of the combination high chair, rocking horse, and desk of FIG. 1 showing our new design as a desk;

FIG. 4 is a right side view of the combination high chair, rocking horse, and desk of FIG. 1. The left side is the same as the right side view;

FIG. 5 is a front view of the combination high chair, rocking horse, and desk of FIG. 1;

FIG. 6 is a rear view of the combination high chair, rocking horse, and desk of FIG. 1;

FIG. 7 is a bottom view of the combination high chair, rocking horse, and desk of FIG. 1; and,

FIG. 8 is a top view of the combination high chair, rocking horse, and desk of FIG. 1.
